GUSTAF I. SUNDSTROM, OF ROCHESTER, NEW YORK, ASSIGNOR TO SHUR-ON STANDARD OPTICAL COMPANY, INC., OF GENEVA, NEW YORK

DESIGN FOR A NOSE BRIDGE FOR SPECTACLES

Application filed May 11, 1929. Serial No. 31,177. Term of patent 14 years.

To all whom it may concern:

Be it known that I, GUSTAF I. SUNDSTROM, a citizen of the United States, residing at No. 122 Vermont Street, in the city of Rochester, county of Monroe, and State of New York, have invented a new, original, and ornamental Design for a Nose Bridge for Spectacles, of which the following is a specification, reference being had to the accompanying drawing, forming part thereof,

In the drawings:

Fig. 1 is a front view of a nose bridge for spectacles, showing my new design; and

Fig. 2 is a top view.

I claim:

The ornamental design for a nose bridge for spectacles, as shown.

GUSTAF I. SUNDSTROM.
